SIGNAL

Michael Corpora, San Jose, Calif.

Application September 13, 1932, Serial No. 632,940

1 Claim. (Cl. 175—337)

The present invention relates particularly to that type of signals mountable upon a motor vehicle and operated by the driver thereof to indicate a proposed action, that is, whether he is 5 going to slow down or stop, or turn to the left, or turn to the right.

It is the object of the invention to provide a device of the character indicated that may be operated by a small amount of electrical current 10 from the battery of the vehicle.

It is another object of the invention to provide a device of the character indicated that will be small and compact in form, economical to manufacture, of few parts, simple in construction, 15 strong, durable, positive in operation, and highly efficient in its practical application.

In the drawing:

Figure 1 is a side elevation of a device embodying my invention, partly in section and parts 20 broken away.

Figure 2 is a view on line 2—2 of Figure 1.

Figure 3 is a view on line 3—3 of Figure 1.

Figure 4 is a diagrammatical illustration showing the wiring system embodied in the device.

25 Referring now more particularly to the specific embodiment of the invention herein disclosed, I show at 1 a frame mounted in any suitable manner, as at 2, upon the vehicle structure in a position where it may be readily seen from both 30 front and rear.

The three essential operating parts of the device are identical in construction, therefore but one part will be described in detail, similar portions of the other two parts being indicated by 35 similar reference characters followed by the letter "a" in one case and by the letter "b" in the other.

Mounted, then, upon the lower end of the frame is a plate 3, the plate being circular in form and 40 provided with bosses 4 which slidably engage the two side rods of the frame, the plate being held fixedly thereon by means of set screws 5. In this plate are disposed symmetrically arranged electromagnets as 6, the magnets being connected in 45 an electrical circuit 7 including terminal 8, switch 9, battery 10 grounded at 11. In the center of the plate, and centrally disposed with relation to the four magnets, is formed a bearing 12.

At 13 is shown an operating rod having sliding 50 engagement with the bearing 12, and also with bearings 12a and 12b. To the upper end of this rod is attached a cable 14 which passes over a small pulley 15 on shaft 16, and then over a larger pulley 17 on shaft 18. On the shaft 18 is 55 mounted signal arm 19 which is moved into posi-

tions 20, 21, 22 when the rod 13 is pulled downwardly as hereinafter described.

At 23 is shown a disc of magnetic material such as steel capped with plate of nonmagnetic material as at 24. The rod 13 passes centrally 60 through this element which is mounted thereon by means of a screw 25 engaging a groove 26. Formed in the bottom surface of part 23, and on opposite sides of the rod 13, are recesses 27 lined with a nonmagnetic material as at 28. At 65 29 is a small disc of magnetic material mounted upon a nonmagnetic bolt 30 which passes through, and has sliding engagement with, disc 23. The bolt 30 is of such a length that the disc 29 is suspended below the disc 23 when the 70 device is in an inoperative position.

When the device is assembled as described the discs 29 overlie portions of two of the magnets 6 as shown in dotted lines at 31 in Figure 2, the rest of the magnets being exposed to act 75 upon the overlying disc 23.

If it is desired to swing arm 19 to position 20, then circuit 7b is closed and magnets 6b are energized. The energized magnets 6b pull discs 29b down into contact with them, and in doing 80 so bring disc 23b into their magnetic fields so that it, too, is pulled down into contact with them, the discs 29b seating in recesses 27b. This downward movement of disc 23b actuated the rod 13 and through it the cable 14 and pulley 17 85 to move the arm 19 into the desired position.

The positions 21 and 22 are attained by moving the switch through 8b to 8a and thence to 8 where the discs 23a and 23 are moved into range and acted upon by their respective magnets. 90

The weight of the elements 23, 23a, 23b are such that they nearly balance the arm 19 and working parts so that the work of the magnets is reduced to a minimum, the parts returning to their normal positions when the magnets are 95 deenergized by the overbalancing weight of the arm 19.

It is to be understood, of course, that while I have herein shown and described but one specific embodiment of the invention, changes in 100 form, construction and method of assembly and operation may be made within the scope of the appended claim.

I claim:

In an assembly of the character described a 105 fixedly supported magnet and means for energizing the same, a rod slidably mounted relative thereto, a magnetic element mounted on the rod to overlie the magnet and normally held in spaced relation thereto by said rod, a magnetic 110

disc suspended from said element, and slidable relative thereto, said element having a recess formed therein to receive said disc, the disc being disposed within the magnetic field of the magnet and drawn into contact therewith when the magnet is energized, and the element being

disposed in the magnetic field of the magnet when the disc is in the last named position and drawn into contact therewith when the disc is in the last named position, whereby to move the rod.
